Leot. DuMais.

Inventor:
Kurt Nebel
by Ross R. Stoll.

UNITED STATES PATENT OFFICE.

KURT NEBEL, OF CHICAGO, ILLINOIS.

LIFE-PRESERVER.

1,202,207.

Specification of Letters Patent. Patented Oct. 24, 1916.

Application filed December 20, 1915. Serial No. 67,892.

To all whom it may concern:

Be it known that I, KURT NEBEL, a subject of the Emperor of Germany, residing at 2925 South Park avenue, in the city of Chicago, county of Cook, and State of Illinois, have invented certain new and useful Improvements in Life-Preservers, of which the following is a specification.

My invention relates to improvements in life preservers, and particularly to devices of this class which are inflated.

The objects of my invention are to so construct and arrange the device that it will be automatically inflated by exposure to or immersion in water, and so that it may be readily attached to a person in position for instant use and with parts thereof surrounding the body of the person and other parts collapsed flat against the body.

These and other objects I accomplish as hereinafter described and as more particularly pointed out in the appended claims, reference being had to the accompanying drawings in which an embodiment of my improved life preserver is shown.

In the drawings: Figure 1, represents a view of my improved life preserver, partially in perspective and partially in central vertical section with the gas bag expanded. Fig. 2, is a side elevation of my improved device with the gas bag collapsed. Fig. 3, is an enlarged detached detail view of the dissolvable holding loop for the gas bag. Fig. 4, is an enlarged fragmentary view of one of the water inlet valves in the gas bag.

In referring to the adaptation of my invention shown in the accompanying drawings in detail, like numerals designate like and corresponding parts.

My improved apparatus comprises an inflatable tube 1, a gas bag 2 which is connected to the tube 1, by a flexible pipe or pipes 3, and a device for containing gas generating material attached to the gas bag. The tube 1, is constructed of rubber or other soft yielding resilient material and preferably with two ends to one of which a buckle 4 is connected and to the other a strap 5, which can be fastened in the buckle to fasten the tube around the body of a person or in a substantially circular endless condition. The gas bag 2, is preferably formed of flexible rubber or like material and the pipes 3 which serve to connect the bag to the tube is likewise of similar material.

These pipes also act as conducting pipes for the gas from the bag to the tube as will appear farther on.

One or more inlet valves are arranged in the gas bag for admitting water to the interior of the bag when it is immersed. These valves are preferably formed as shown in Fig. 4, and comprise a tubular member 6, which is fitted in an opening in the gas bag and has a valve seat 7, at its inner end, a valve 8, in said tubular member having a stem 9, and a comparatively weak spring 10, for normally holding said valve in closed position.

The container for the gas generating material is preferably composed of a hollow flat circular body 11, and a tube 12, extending up from said body which is fitted through an opening in the gas bag as shown in Fig. 1, and clamped firmly in place therein between two nuts 13 and 14. The upper portion of the tube which projects within the gas bag is preferably perforated as shown at 15, in Fig. 1 and the top 16 closed to prevent the water flowing too rapidly to the gas generating material 17, preferably carbide in the body 11. The body 11, and tube 12, are preferably constructed of light metal and can be easily detached from the gas bag for cleaning purposes or for refilling with material by removing the nuts 13 and 14.

When the bag is in its collapsed position it is preferably held in a flat condition as shown in Fig. 2, by means of a loop 18, which is fitted around the middle of the bag, and in order to permit the bag to distend and resume its natural round condition the loop 18 is constructed of flexible material which will dissolve when immersed in water. For this purpose I prefer gelatin or a dissolvable composition which will quickly disintegrate under the action of water.

As shown in Fig. 3, the loop 18 is made in U-shape with a separate fastener 19, fitted over the ends 20 of the loop which are oppositely bent or curved to receive and hold the fastener.

The operation of this improved device is as follows:—The tube is fitted in place around the body of a person, with the gas bag collapsed flat against the body and the container filled with carbide. When a person so equipped becomes immersed in water, the loop is immediately dissolved freeing the gas bag and permitting it to assume its natural

round shape. The expansion of the gas bag coupled with the exterior water pressure opens the inlet valves allowing the water to flow into the gas bag and through the openings in the tube 12, down upon the carbid thereby instantly generating gas which flows upward into the gas bag and the tube 1, expanding the tube 1, sufficiently to sustain the weight of the wearer.

10 This improved device can also be utilized as a life saving buoy by throwing it into the water.

While I have illustrated and described a preferred form of construction for carrying my invention into effect, this is capable of a wide range of variation, alteration, modification and change without departing from the spirit of my invention, I therefore do not wish to be limited to the construction herein shown and described, but desire to avail myself of all such variations, alterations, modifications and changes as fairly fall within the scope of the appended claims or may be construed to be within the scope thereof by involving the doctrine of equivalents.

What I claim as my invention and desire to secure by Letters Patent is:—

1. In a device of the class described, an inflatable tube adapted to be fastened around the body of the wearer, a gas bag suspended beneath said tube by piping, a gas generating device connected to the lower portion of the gas bag, and a loop element fitted around the gas bag for maintaining said bag in a collapsed condition, said loop being soluble in water.

2. In a device of the class described, an inflatable tube adapted to be fastened around the body of the wearer, a gas bag suspended beneath said tube by piping, a gas generating device connected to the lower portion of the gas bag, and a loop element of gelatin and soluble in water fitted around the gas bag.

3. In a device of the class described, an inflatable tube, a gas bag suspended beneath said tube, said gas bag having water inlet valves, and a gas generating device connected to the lower portion of the gas bag.

4. In a device of the class described, an inflatable tube, a gas bag suspended beneath said tube, said gas bag having water inlet valves, and a gas generating device connected to the lower portion of the gas bag; said

gas generating device comprising a hollow flat body and a tube extending from said body and fitted through and clamped in an opening in said gas bag.

5. In a device of the class described, an inflatable tube, a gas bag suspended beneath said tube, said gas bag having water inlet valves, and a gas generating device connected to the lower portion of the gas bag; said gas generating device comprising a hollow flat body and a tube extending from said body and fitted through and clamped in an opening in said gas bag, the upper portion of the tube projecting within the gas bag and being provided with perforations.

6. In a device of the class described, an inflatable tube, a gas bag suspended beneath said tube, said gas bag having water inlet valves, and a gas generating device connected to the lower portion of the gas bag; said gas generating device comprising a hollow flat body and a tube extending from said body and fitted through and clamped in an opening in said gas bag, the tube being closed at the top and the upper portion of said tube projecting within the gas bag and being provided with perforations in its side wall.

7. In a device of the class described, a container for carbid having an upwardly extending tube, a collapsible gas bag having an opening in which said tube is secured and a water inlet valve, and means for attaching the gas bag to the body of the wearer, said means including an inflatable tube adapted to be filled with gas from the gas bag.

8. In a device of the class described, an inflatable tube, a gas bag suspended beneath said tube by piping, and a gas generating device connected to the lower portion of the gas bag.

9. In a device of the class described, a container for carbid having an upwardly extending tube, a collapsible gas bag having an opening in which said tube is secured, and a water inlet valve, an inflatable tube adapted to be fitted around the body of a person and a pipe depending from said tube to which the gas bag is secured.

In testimony whereof I have hereunto set my hand.

KURT NEBEL.
